CLAIM

The ornamental design for a saw table, substantially as shown and described.

DESCRIPTION

FIG. 1 is a perspective view of a saw table showing our new design;

FIG. 2 is a side elevational view taken from the left of FIG. 1;

FIG. 3 is a top plan view thereof; and

FIG. 4 is a rear elevational view thereof.

*Fig. 1.**Fig. 2.**Fig. 3.**Fig. 4.*
